UNITED STATES PATENT OFFICE.

HAROLD J. GOSS, OF NASHUA, NEW HAMPSHIRE, ASSIGNOR TO THE INTERNATIONAL PAPER BOX MACHINE COMPANY, OF NASHUA, NEW HAMPSHIRE, A CORPORATION OF MAINE.

MACHINE FOR MAKING SET-UP BOXES.

Application filed November 7, 1921. Serial No. 513,275.

To all whom it may concern:

Be it known that I, HAROLD J. Goss, a citizen of the United States, and resident of Nashua, in the county of Hillsborough and 5 State of New Hampshire, have invented certain new and useful Improvements in Machines for Making Set-Up Boxes, of which the following is a specification.

This invention relates to the manufacture 10 of paper board boxes and has particular reference to machines for making rectangular boxes in set up form, ready to have goods placed therein. The boxes made by this machine are referred to as wall boxes for the 15 reason that, when made, they present upright side portions which serve as walls to retain goods.

The object of the invention is to provide 20 an improved machine which is rapid and automatic in operation, the blanks being fed singly and successively to the machine, folded therein, and delivered therefrom in firmly set-up condition.

With this object in view the invention consists 25 in the construction and combination of parts substantially as hereinafter described and claimed.

Of the accompanying drawings, in which similar reference characters indicate similar 30 parts in all of the views:

Figure 1 is a plan view of the machine.

Figure 2 represents a section on line 2—2 of Figure 1.

Figure 3 is a detail view on a larger scale 35 looking in the direction of arrow 3 in Figure 2.

Figure 4 represents a section on line 4—4 of Figure 3, on a still larger scale.

Figure 5 is a detail sectional view herein- 40 after referred to.

Figure 6 is a detail plan view illustrating how each blank is stopped and registered in position for the plunger to operate on it.

Figure 7 is a detail sectional elevation 45 looking in the direction of arrow 7, Figure 6.

Figure 8 is a perspective view of a box made by the machine, partially broken out to more clearly show the folds.

50 Figure 9 is a plan view of one of the flat blanks.

Similar reference characters indicate similar parts in all of the views.

A suitable framework of the machine 55 comprises side members 12 and tie rods some

of which are designated by 13 and others of which will be referred to hereinafter.

The machine illustrated is designed to operate upon blanks substantially of the shape shown in Figure 9, to make boxes illustrated 60 by Figure 8. Each blank comprises a central portion *a*, wall portions *b b*, and flaps *c d d* which latter when the box is completed, form its end walls.

From a suitable table, not shown, the 65 blanks are fed singly and successively by a pair of friction feed wheels 14 carried by a shaft 15. Below the feed wheels and cooperating with them are rolls 16 carried by a shaft 17, the two shafts 15, 17, having suitable intermeshing gears the upper one of which is indicated at 18 in Figure 1.

Each blank fed passes onto a platform comprising horizontal stationary strips 19 (Fig. 1), lateral portions of the blank passing into and through restricted throats or guideways existing between two pairs of upper and lower vertical strips 20, 21, (Figs. 1 and 2).

Two endless chains 22 having spaced lugs 23 are mounted on sprockets carried by shaft 17, a forward shaft 24, and a lower shaft 25, the latter being mounted in arms 26 supported by one of the tie rods 13. The sprockets on shaft 24 run loosely thereon. 85

As soon as the rear edge of a blank passes from between the wheels or rolls 14, 16, so as to be no longer advanced thereby, the friction between the blank and the strips 19, 20, 21, causes it to stop until its rear edge 90 is engaged by a pair of lugs 23 of the chains 22 the upper stretches of which travel in a plane slightly below the plane of the guideways between the strips 20, 21. The blank is not only "squared up" by the pair of lugs, 95 but is positively advanced thereby. This positive feed, in connection with the restricted or narrow guideways, is important because of the resistance offered by the flap deflectors or breakers presently described. 100

Since glue must not be deposited on all the flaps *c* and *d*, means are provided to cause them to shift to different relative planes of travel. As soon as the blank starts to move off from the platform strips 19 its 10 two middle flaps *c*, *c* which are longer than the corner flaps *d d* ride onto inclined deflectors 27 supported by rods 28 projecting from the strips 21. These deflectors are laterally adjustable on the rods 28, and they 11

are set far enough apart to engage only the flaps *c*, *c*. Said deflectors do not lift the flaps *c*, *c* far, but only enough so they will be guided over the higher ends of two rearwardly and downwardly inclined breaker rods or deflectors 29.

As shown by comparing Figures 1 and 2, the breaker rods 29 are so spaced and inclined that (the flaps *c* passing above them as described) the flaps *d*, *d* will first pass under their higher outer ends and then be bent or "broken" down to substantially vertical positions alongside of the outer surfaces of the strips 21. The lower inner ends of the rods 29 guide the flaps *d*, *d*, in vertical positions into narrow passageways between the outer faces of the strips 21 and the inner walls of two glue boxes 30, thereby ensuring complete "breaking" of said flaps on their crease lines.

As the longer flaps *c*, *c* have only been slightly deflected, they spring back to substantially horizontal positions after passing the deflectors, and said flaps ride over the tops of the glue boxes, the latter having wide glue wheels 31 to apply a film of glue to the under surface of each of the two flaps *c*, *c*. To render it certain that the flaps *c*, *c* will pass onto the glue boxes inclined guide fingers 32 project from said boxes. And to render it certain that said flaps will contact with the glue wheels, suitable upper rolls 33 are provided as indicated in Figure 2.

Each blank now, with its flaps *d*, *d* broken down but usually inclined somewhat outwardly, and with its flaps *c*, *c* standing out, passes between upper and lower belts 34, 35. By means of gearing not necessary to describe in detail the belts 34, 35, are speeded up to travel faster than the chains 22, whereby the blanks are drawn away from the chain lugs before the latter begin to move down around the sprockets of shaft 24. Said speed belts also act to increase the momentum of the blanks so as to aid in discharging them to position over the plunger hereinafter described. As illustrated in Figure 2, these belts are mounted and driven so that their contacting operative stretches first take each blank horizontally and then deliver it in a downwardly inclined direction above an upwardly movable plunger 36. One reason for this inclination is, as will be referred to again hereinafter, that upon the completion of the folding of the blank to box form it automatically tips away in a predetermined direction, which could not reliably occur if the movement was in a vertical direction. Another reason for the delivery of the blank in a downwardly inclined direction is to cause it to automatically gravitate to accurate position for folding, as will now be described.

Each blank rapidly discharged by the

belts 34, 35, slides down two inclined rods 37 (Figs. 2, 6 and 7), until the forward edges of the flaps *c*, *c* contact with stops 38 carried by blocks 39 adjustably mounted on said rods. The upper ends of the rods 70 are at a right angle and are clamped in blocks 40 having pins 41 secured in blocks 42 laterally adjustable upon a shaft or tie rod 43. It is to be understood that the lower pulley for the belt 35 rotates on said shaft 75 or tie rod.

It is important that the blank shall be laterally registered in position. To this end outwardly flaring guides 44 are provided, each having its pin 45 adjustably 80 fitting a bearing in a block 39. Each blank, as its flaps *c* approach the stops 38, is guided to correct lateral position by the extreme edges of the flaps *c* contacting with the inner faces of the two flaring guides 44.

After a blank has been stopped in registered position it is lifted by the plunger 36 (Fig. 2) the shank or rod 46 of which is mounted to reciprocate in bearings 47 supported by tie rods 48. A link 49 is connected at one end to the rod 46 and at the other end to a lever arm 50 pivotally mounted on a tie rod 51 and having a shorter arm 52 actuated by a cam (not necessary to illustrate) carried by shaft 53.

When the plunger moves up, it engages the central portion of the blank and causes the flaps thereof to pass folder fingers which will now be described.

Mounted on two tie rods 54, 55 (Figs. 1, 2, 3 and 4) so as to be laterally adjusted thereon, are the sleeve members 56 of two frames, the two sleeve members of each frame being connected by webs or bars 57. The space between these two frames forms the chamber in which the box is compressed endwise after the blank has been folded to approximate form. This folding is effected by front and rear curved fingers 58 and side or end curved fingers 59. When the blank is pushed up, bottom first, by the rising plunger 36, the wall portions *b*, *b* of the blank ride against the front and rear fingers 58 and are held back so that they swing down on their crease lines. Since the flaps *d*, *d* of said portions *b*, *b* have been already broken down, as previously described, this downward swinging of the portions *b*, *b* causes the flaps *d*, *d* to move in under the unbroken middle flaps *c*, which flaps *c* carry glue on their under surfaces. Continued pushing of the blank up toward and between the upper ends of the four sets of fingers results in the portions *b*, *b* being carried in close to the front and rear faces of the plunger, and the closing of the flaps *d*, *d*, *c* in close to the ends of the plunger, with the glued flaps *c* outermost. The flaps *d*, *d* are of such length that their end edges practically meet, while the area of each flap *c* is 130

such as to cover and adhere to the entire area of the two flaps *d d* under it.

The fingers of each series 58 are carried by and depend from a bar 60 Figs. 2 and 4.

5 The two bars 60 are adjustable toward and from each other to suit different sizes of boxes to be made. It is to be understood of course that the plunger 36 is removably connected with its rod 46 to permit the substitution of one of different size or shape therefor. The bars 60 are mounted in brackets mounted on the tie rods 54, 55, and are adjustable relatively to the center of the forming space by screws 61.

15 The fingers of each series 59 are carried by and depend from a plate 62 carried by the inner end of a slide 63 (Figs. 3 and 4) mounted to reciprocate in a bar 57. Toggle links 64 are pivotally connected at one end

20 to the slide 63 and at the other end to a bracket 65 rigidly connected with the outer bar 57. Mounted on the center pivot of the toggle links is a block 66 having a pin 67 extending into a block 68 pivotally mounted

25 in the forked end of an arm 69 of a rock shaft 70. A spring 71 surrounding the pin 67 and confined between the blocks 66, 68, causes the arm 69 to actuate the toggle yielding. As shown in Figures 1 and 3 there

30 are two of the toggle mechanisms just described so that, when the rock shaft is actuated, the two plates 62 are caused to press yieldingly on the overlapped flaps of the box, which flaps are then backed by the end

35 walls of the plunger, the result of which is to secure firm adherence of the entire gummed areas of said flaps. A rock shaft 70 has an arm 72 at one end (Fig. 1, 2 and 3) said arm having a link 73 pivoted to it, the

40 other end of the link being actuated by a suitable cam carried by the shaft 53.

After the blank has been folded over the plunger as described, the pressing plates move apart and the plunger moves down.

45 But the completed box does not move down with the plunger. It is stripped therefrom in the sense that it is temporarily held in the location where it was formed while the plunger descends out of it. This effect is

50 obtained by a pair of spring-pressed latches or pawls 74 (Figs. 4 and 5). Each pawl 74 is pivoted at 75 to a block 76 adjustably mounted on one of the bars 60, said pawl projecting upwardly and backed by a spring

55 77. The two pawls yield when the plunger moves up, with a blank mounted thereon, and the upper ends or tips of the pawls are at a height to snap under the lower edge of one of the portions *b* of the folded blank

60 before the plunger moves down. Then when the plunger returns to lower position the box is retained loosely, by the pawls, in the upper portion of the chamber or space in which it was formed. When the plunger

65 rises with another blank the latter dislodges

the formed box from its loose inclined position so that said formed box will fall over the rod 55 into any suitable receptacle or onto any suitable belt carrier not necessary to illustrate.

70 As indicated in Figure 4, the plunger 36 has grooves 78 in its side face to enable it to pass the strippers 74 on its return, without catching upon them.

75 In order that each box may be temporarily held under sufficient endwise pressure to ensure the setting of the glue, I may provide pressure devices such as indicated in Figure 4, consisting of a pair of flat spring strips 79 carried by upwardly extending bars 80 supported by two of the cross webs or bars 57.

80 As the mechanism for driving the different parts of the machine in proper timed relationship may be of any preferred kind, 85 and as such mechanism is not specifically claimed herein, a detailed description thereof is unnecessary. It is sufficient to explain that:—

85 When the machine is operated, blanks are 90 successively delivered upon the platform strips. Each blank so delivered remains stationary until its rear edge is engaged by a pair of chain lugs 23 and carried forward thereby. The friction between the blank 95 and said platform, aided by the friction on the blanks caused by the narrow guideways or throats between the strips 20, 21, tends to so hold the blank back against the chain lugs which are pushing it that the blank 100 is advanced past the flap deflectors and breakers and gluers in accurate squared up position and so reaches the gripping and carrying belts 34, 35. During this portion of the travel of the blank, the rods 29 not 105 only break down the corner flaps *d, d*, while the intermediate flaps *c* remain in outwardly extending positions or planes and receive glue, but said rods 29 also ensure such action on the corner flaps that they will pass 110 along hanging down and ready to swing inside of the flaps *c* as soon as the portions *b b* are (later) bent down when the plunger rises.

115 Each blank, with its corner flaps hanging down and its flaps *c* standing out is rapidly delivered or "shot" by the speed belts 34, 35, over the top of the plunger, and down against the stops 38 and, if not in accurate lateral position, is guided to that position 120 by the side guides 44.

125 As the operation of the plunger, coacting with the folding fingers 58, 59, has been described, further reference thereto is unnecessary.

Having now described my invention, I claim:

1. A box-making machine having folding instrumentalities and means for ensuring delivery of blanks thereto in squared-up po- 130

1. **sitions, said means comprising a stationary platform for frictionally detaining blanks singly thereon and endless lug carriers for removing the blanks from said platform and 5 forwarding them to be folded.**
2. **A box-making machine having folding instrumentalities and means for ensuring delivery of blanks thereto in squared-up positions, said means comprising a plurality of laterally spaced stationary strips for frictionally detaining blanks singly thereon, and endless chains having lugs to successively engage blanks on said strips and forward them to be folded.**
3. **A box-making machine having folding instrumentalities and means for ensuring delivery of blanks thereto in squared-up positions, said means comprising a stationary platform for frictionally detaining blanks singly thereon and endless lug carriers for removing the blanks from said platform and 10 forwarding them to be folded, narrow throats or guideways being provided for laterally projecting portions of the blanks.**
4. **A machine for making wall boxes, comprising a guideway formed to direct a blank having flaps with the flaps projecting laterally from the guideway, means for advancing the blank along said guideway, 15 means for deflecting the flaps into different paths of travel, means for applying glue to two oppositely projecting flaps, and means for folding the blank with its flap in overlapping relationship.**
5. **A machine for making wall boxes from blanks having corner flaps and intermediate flaps, comprising means for causing said blanks to travel, means for bending the corner flaps down while travelling, means for 20 applying glue to the intermediate flaps while extending outwardly, and means for folding the blanks with said flaps in overlapping relationship.**
6. **A machine for making wall boxes from blanks having corner flaps and intermediate flaps, comprising means for causing said blanks to travel, a pair of gluers, means for directing the intermediate flaps over the gluers, means for breaking the corner flaps 25 down and directing them inside the inner walls of the gluers, and means for folding the blanks with their corner flaps inside the intermediate flaps.**
7. **A machine of the character described, 30 having two guideways for flat blanks, each of said guideways comprising straight upper and lower members in closely spaced relationship, means for advancing blanks along said guideways with flap portions projecting therefrom, and means for breaking some of the flaps and applying glue to other flaps while the blanks are travelling along the guideways.**
8. **A machine of the character described, 35 having means for causing blanks to travel, means for causing flaps of the blanks to be broken and other flaps to receive glue while traveling, upper and lower faster-traveling belts for receiving the blanks after said action upon flaps thereof, and folding instrumentalities to which the blanks are delivered by said belts.**
9. **A machine of the character described having chains provided with lugs for causing blanks to travel, means for breaking some of the blank flaps and gluing others while traveling, upper and lower belts travelling faster than the chains for taking the blanks therefrom, and folding instrumentalities to which the blanks are delivered 40 by said belts.**
10. **A machine of the character described having folding instrumentalities including a plunger, stop devices for determining the position of a blank relatively to the plunger, 45 belts for forcibly discharging a blank against said stop devices, and means for delivering a blank to said belts with its flap portions in condition for treatment by the said folding instrumentalities.**
11. **In a machine of the character described, an upwardly movable plunger, downwardly extending stationary fingers at two opposite sides of the path of movement of the plunger, pressers movable toward and 50 from the plunger at the other two sides of its path of movement, downwardly extending fingers carried by said pressers, and means for delivering foldable blanks above the plunger while the latter is in lower position.**
12. **In a machine of the character described, an upwardly movable plunger, means for delivering a foldable blank above the plunger while it is down, downwardly 55 extending stationary fingers spaced to cooperate with two opposite faces of the plunger to fold portions of a blank when the plunger moves up, pressing plates spaced to cooperate with two other faces of the plunger, means for moving said plates toward the plunger when it is up, and downwardly extending fingers carried by said plates.**
13. **In a machine of the character described, an upwardly movable plunger, 60 means for supporting a blank above the plunger, means including side pressers having downwardly extending fingers for cooperating with the plunger to effect folding of the blank, means for delivering blanks singly and successively onto said supports, and stop devices for registering the position of each blank on the supports.**
14. **In a machine of the character described, a plunger movable in an upwardly 65 inclined direction, a pair of inclined rods to support a blank to be lifted therefrom by the plunger, means for folding portions of**

the blank against the sides of the plunger when the latter moves up, and stop devices adjustably mounted on said rods.

15. In a machine of the character described, a plunger movable in an upwardly inclined direction, a pair of inclined rods to support a blank to be lifted therefrom by the plunger, means for folding portions of the blank against the sides of the plunger 10 when the latter moves up, means for de-

livering a blank edgewise onto said rods, stops carried by said rods for arresting the front edge of the blank, and guides carried by the rods to laterally register the blanks.

In testimony whereof I have affixed my 15 signature.

HAROLD J. GOSS.
